(57) **CLAIM**

The ornamental design for a solar module, as shown and described.

DESCRIPTION

FIG. 1 is a top plan view of a solar module;

FIG. 2 is a bottom plan view thereof;

FIG. 3 is a front view thereof;

FIG. 4 is a rear view thereof;

FIG. 5 is a left side view thereof; and

FIG. 6 is a right side view thereof.

FIG. 7 is a top plan view of an alternative embodiment of a solar module;

FIG. 8 is a bottom plan view thereof;

FIG. 9 is a front view thereof;

FIG. 10 is a rear view thereof;

FIG. 11 is a left side view thereof; and

FIG. 12 is a right side view thereof.

FIG. 13 is a top plan view of an alternative embodiment of a solar module;

FIG. 14 is a bottom plan view thereof;

FIG. 15 is a front view thereof;

FIG. 16 is a rear view thereof;

FIG. 17 is a left side view thereof; and

FIG. 18 is a right side view thereof.

FIG. 19 is a top plan view of an alternative embodiment of a solar module;

FIG. 20 is a bottom plan view thereof;

FIG. 21 is a front view thereof;

FIG. 22 is a rear view thereof;

FIG. 23 is a left side view thereof; and

FIG. 24 is a right side view thereof.

FIG. 25 is a top plan view of an alternative embodiment of a solar module;

FIG. 26 is a bottom plan view thereof;

FIG. 27 is a front view thereof;

FIG. 28 is a rear view thereof;

FIG. 29 is a left side view thereof; and

FIG. 30 is a right side view thereof.

FIG. 31 is a top plan view of an alternative embodiment of a solar module;

FIG. 32 is a bottom plan view thereof;

FIG. 33 is a front view thereof;

FIG. 34 is a rear view thereof;

FIG. 35 is a left side view thereof; and,

FIG. 36 is a right side view thereof.

The broken lines shown represent unclaimed subject matter and form no part of the claim design.
